UNITED STATES PATENT OFFICE.

WILLIAM C. BLACKMOND AND GUY EVERETT STOY, OF GALVESTON, TEXAS.

BRICK-FIRE-BOX CONSTRUCTION.

1,003,392.

Specification of Letters Patent. Patented Sept. 12, 1911.

Original application filed March 25, 1909, Serial No. 485,824. Divided and this application filed December 12, 1910. Serial No. 596,955.

To all whom it may concern:

Be it known that we, WILLIAM C. BLACKMOND and GUY EVERETT STOY, both citizens of the United States, residing at Galveston, in 5 the county of Galveston and State of Texas, have invented certain new and useful Improvements in Brick-Fire-Box Construction; and we do hereby declare the following to be a full, clear, and exact description 10 of the invention, such as will enable others skilled in the art to which it appertains to make and use the same.

This invention relates to improvements in fire box construction and more particularly to the lining for a fire box of a locomotive using oil as fuel, and is a divisional application of our former Patent No. 962,301, dated June 21, 1910.

The object of the present invention is to 20 provide a fire box lining which is constructed of interlocking bricks so arranged that same may not be shaken apart by the vibration of the locomotive.

Another object of the invention is to 25 provide a fire box lining formed of bricks which are firmly held in place without the use of cement, and can be readily disassembled by removing one of the side or end bricks.

With the above and other objects in view, 30 as will be more fully understood as the description proceeds, the invention consists in certain combinations and arrangement of the parts hereinafter described and illustrated in the accompanying drawings.

35 In the accompanying drawings forming a part of this specification, like characters of reference indicate corresponding parts.

Figure 1 is a longitudinal section of a fire box constructed in accordance with our invention. Fig. 2 is a plan view of the lining removed from the casing. Fig. 3 shows a side elevation and plan of one of the corner bricks. Fig. 4 shows a side elevation and plan of an end brick. Fig. 5 shows a side 45 elevation and plan of another corner brick, and Fig. 6 shows a side and edge elevation and also a plan of the form of bricks used in the side walls of the fire box.

Referring to the drawings, 1 represents 50 an ordinary locomotive fire box provided with a lining of interlocking bricks in assembled position. The end walls are composed of corner bricks 2, 3, 4 and 5 having oppositely inclined edges 6 and made larger 55 at the bottom. The inclined edges of said

bricks are provided with longitudinally extending tongues 7, for a purpose hereinafter explained. The corner brick 3 is preferably provided with a right angular portion 8 for abutting against the side wall brick to 60 be presently described. The corner bricks 2 and 4 have vertical angular recesses 9 for receiving the side wall bricks and the corner brick 5 is formed with a plain inner side. The end bricks 10 taper toward the bottom 65 and form a wedge, the inclined edges of which are provided with longitudinal grooves 11 for receiving the tongues 7 of the corner bricks.

The bottom is composed of ordinary flat 70 bricks 12 arranged transversely of the fire box in a central position and are of such a length as to have a space at each end thereof for the lower ends of the side wall bricks. As shown in Fig. 6 of the drawings, each side brick consists of a flat body 13, having integrally formed therewith, a lateral off-set portion 14 which inclines inwardly from the upper edge preferably on a curve and the lower inner edge of said 75 off-set portion is provided with a recess as at 15, to form a ledge for overlapping the ends of the bottom bricks.

From the foregoing description taken in 80 connection with the drawings, it is apparent 85 that when the bricks are in assembled positions, (as best illustrated in Fig. 2 of the drawings), the bottom bricks are held in place by the side bricks, the end wedge bricks force the corner bricks against the 90 adjacent side wall bricks and an interlocked lining constructed in this manner will be securely held in position. By lifting one of the side bricks or an end wedge brick 95 perpendicularly, the lining can be readily disassembled and removed for the purpose of repairs, or replaced by a new lining.

It is to be understood that slight changes in the form, proportion and minor details of construction may be resorted to without 100 departing from the spirit of the invention.

What we claim and desire to secure by Letters Patent is:—

1. In a fire box lining, the combination 105 of corner bricks having enlarged bases, bottom bricks abutting the inner sides of the corner bricks, side bricks having inwardly projecting ledges adapted to overlap the bottom bricks, and wedge-shaped end bricks interposed between the corner bricks to 110

- force them outwardly toward the side bricks.
2. In a fire box lining, the combination of corner bricks having oppositely inclined edges forming enlarged bases, the inclined edges of the corner bricks being provided with longitudinally extending tongues, bottom bricks abutting the inner faces of the corner bricks, side bricks having inwardly projecting ledges adapted to overlap the bottom bricks, wedge-shaped end bricks adapted to be interposed between the corner bricks, and the inclined edges of said wedge-shaped bricks being provided with longitudinal grooves to receive the tongues on the corner bricks.
3. In a fire box lining, the combination of corner bricks having oppositely inclined edges forming enlarged bases, the inclined edges of the corner bricks being provided with longitudinally extending tongues, bottom bricks abutting the inner faces of the corner bricks, side bricks having inclined off-set portions adapted to overlap the ends of the bottom bricks and the vertical edges thereof abutting the adjacent side bricks, wedge-shaped end bricks adapted to be interposed between the corner bricks, and the inclined edges of said wedge-shaped bricks being provided with longitudinal grooves to receive the tongues on the corner bricks.
4. In a fire box lining, the combination of corner bricks having oppositely inclined edges forming enlarged bases, the inclined edges of the corner bricks being provided with longitudinally extending tongues, bottom bricks abutting the inner faces of the corner bricks, side bricks having inwardly curved off-set portions adapted to overlap the ends of the bottom bricks and the vertical edges thereof abutting the adjacent bricks, one of the corner bricks having an angular portion for fitting against the first side brick to fill the space its off-set portion makes therewith, two of the other corner bricks diagonally opposite each other having recesses therein for receiving the vertical edges of the adjacent side bricks, wedge-shaped end bricks adapted to be interposed between the corner bricks, and the inclined edges of said wedge-shaped bricks being provided with longitudinal grooves to receive the tongues of the corner bricks. 35 40 45 50

In testimony whereof, we affix our signatures, in presence of two witnesses.

WILLIAM C. BLACKMOND.
GUY EVERETT STOY.
